(57) **CLAIM**

The ornamental design for a lighting fixture housing, as shown and described.

DESCRIPTION

FIG. 1 is a perspective view of the claimed design in a typical operational orientation;

FIG. 2 is a top plan view of FIG. 1;

FIG. 3 is a bottom plan view of FIG. 1;

FIG. 4 is a front elevation view of FIG. 1;

FIG. 5 is a back elevation view of FIG. 1;

FIG. 6 is a right side elevation view of FIG. 1; and,

FIG. 7 is a left side elevation view of FIG. 1.

The broken lines in the drawings illustrate unclaimed portions of the lighting fixture housing and form no part of the claimed design.
